UNITED STATES PATENT OFFICE.

SAMUEL B. STEWART, JR., OF SCHENECTADY, NEW YORK, ASSIGNOR TO THE
GENERAL ELECTRIC COMPANY, OF NEW YORK.

CIRCUIT-BREAKER.

SPECIFICATION forming part of Letters Patent No. 675,049, dated May 28, 1901.

Application filed January 21, 1901. Serial No. 43,982. (No model.)

To all whom it may concern:

Be it known that I, SAMUEL B. STEWART, Jr., a citizen of the United States, residing at Schenectady, county of Schenectady, State of New York, have invented certain new and useful Improvements in Circuit-Breakers, (Case No. 1,608,) of which the following is a specification.

This invention relates to circuit-breakers, and is particularly designed for use on trolley-cars or in supply-stations to effect an automatic rupture of the circuit on predetermined overloads or a manual opening of the circuit when necessary.

The object of the invention is to provide a device of this character which will occupy a minimum space, with the operating parts housed under cover and all live parts enclosed to prevent accidents by contact to passengers or employees and which will positively and effectively open circuits carrying heavy currents.

The invention involves various details of construction, the novelty of which will be hereinafter more fully described in the specification and definitely indicated in the claims.

In the accompanying drawings, which illustrate the invention, Figure 1 is a face view, with the cover removed, of a circuit-breaker embodying my improvements. Fig. 2 is a sectional view on a median plane. Fig. 3 is a detail view showing the tripping-action, and Fig. 4 is a diagram of the circuit and tripping devices.

I provide the circuit-breaker with main and shunt contacts, as usual in the construction of circuit-breakers handling large currents of considerable potential. These contacts are indicated at 1 and 2, each forming a bridge-piece adapted when closed to cross-connect two fixed terminals to which the circuit leads. In circuit with the main contacts controlled by the bridging contact 1 is a series coil 3, the connections between the contact-post 4 and the coil being completed by a brass or copper casting of suitable current-carrying capacity. The operative parts are mounted in a cast-iron casing provided with a cover, as indicated in Fig. 2, and are supported on an insulating fireproof wall of slate or similar material, as indicated at 5 in Fig. 2. The heads

of the bolts and screws are buried in order to prevent flashing across live parts of the apparatus to the casing and to prevent leakage from the condensation of moisture or dirt. 55 The bridging contact 1 may be formed of a bundle of copper or phosphor-bronze laminæ, (indicated in Fig. 1,) as usual in the construction of this class of apparatus. The main and shunt contacts are carried by supports linked together by a stud 6 and set at an angle to one another, and preferably a right angle, so as to bring the apparatus within a small compass. One of the elements, shown in the drawings as that supporting the shunt-contact 65 2, is pivoted on a fixed stud 7, supported by a bolt passing through the slate wall 5, and is controlled by a helical spring 8, fixed at one end to a stationary lug 9 and at the other end to the lever carrying the shunt-contact. 70 The link 10 connects the stud 9 with the free end of the support for the main contact 1. The system thus described forms a parallel-motion arrangement by which a lateral movement of the stud 6 opens or closes both contacts, the 75 positioning of which is such that, as usual, the main contact opens first. The circuit is closed by an operating-handle 11, insulated upon the operative parts of the circuit-breaker and its casing, the lever being pivoted on a 80 fixed stud 12 and extending at its free end into the path of the stud 6, this end being shod at the point of engagement with a steel shoe 28, as indicated in dotted lines in Fig. 1. 85 With the parts as thus described a movement of the handle to the left shifts the stud 6 to the right, thereby setting both contacts in closed relation to the circuit and cramping them in position, and the parts are held locked in this position by a pivoted latch 13, having 90 a beveled nose coöoperating with a corresponding beveled shoulder on the support for the main contact at 14. This latch is normally pressed upwardly by a spring 15 and when the circuit is closed drops behind the tapering shoulder at the point 14. It is locked in this position by a pivoted dog or tripping device mounted to turn on the stud 12 and pressed forward by a spring 16. The action will be clear from an examination of Fig. 3, 100 where 17 represents the tripping device and 18 the shoulder which locks the latch 13, and

- thereby holds the circuit closed. This tripping device is provided with a spur or projection 19, which lies in the path of a pin 20, secured to a projection of the operating-lever. It lies also in the path of an extension of an armature 21, which coöperates with the automatic tripping-coil 3. It will thus be seen that, assuming the circuit-breaker to be set in the position shown in Fig. 1, on a predetermined overload governed by the adjustment of a spring 22 the armature 21 is drawn up, thus depressing the spur 19 and knocking the tripping device to the left in a slot formed in the latch 13. The spring 8 then rapidly opens the circuit, the latch 13 being forced out against the light tension of its spring 15 by the tapering wall at 14. On the other hand, if it be desired to open the circuit by the operating-lever the handle 11 is thrown to the right, bringing the pin 20 against the spur 19, and thus opening the circuit. In resetting the circuit the handle 11 is thrown to the left, bringing the free end of the lever against the stud 6 and forcing the contacts against the tension of spring 8 into their closed positions, on attaining which the beveled wall at 14 clears the end of the latch 13, permitting the latter to be forced to its seat, after which the spring-pressed tripping-dog drops behind the latch and locks it in that position. Coöperating with the shunt-contacts is a closed chute having walls of fiber or similar insulating material, across which is a magnetic field set up by a magnet 23, and in this chute are placed the shunt-contacts at which the rupture of the circuit is finally made, auxiliary arcing contacts 24 24^a being employed to prevent burning of the shunt-contacts, these arcing contacts being formed of blocks of copper or brass fastened in place by set-screws or bolts, so as to be removable for renewal when necessary or desirable. The blow-out magnet should be placed in series with the shunt-contacts. A metal plate may be secured over the parts, as indicated at 25 in Fig. 2, to which one end of the supporting-studs may be secured, and a cover 26 may be bolted over the top, so as to completely inclose the parts, being secured by bolts entering the walls of the casing, as indicated in Fig. 1. The framework may be formed of cast-iron, so that the plates of cast-iron 25 25^a may form pole-pieces for establishing the magnetic field in the chute 27.
- 55 What I claim as new, and desire to secure by Letters Patent of the United States, is—
1. A circuit-breaker comprising movable main and shunt contacts pivoted together at an angle, an operating-lever for bringing them into engagement with corresponding fixed contacts, a spring-actuated latch for locking them in engagement, and a tripping device for the latch adapted to be set and released by opposite handle movements.
  - 65 2. A circuit-breaker comprising movable main and shunt contacts pivoted together, a

spring controlling them giving a normal bias toward an open position, an operating-lever, a spring-actuated latch for locking them in closed relation to corresponding fixed contacts, and a tripping device for the latch, adapted to be set and released by opposite movements of the handle.

3. A circuit-breaker comprising movable main and shunt contacts pivoted together at an angle, a fixed stud on which one of them is pivoted, a supporting-link connected to the other, an operating-lever for shifting the contacts into closed relation to corresponding fixed contacts, a latch for locking them when closed, and a tripping device operated by the lever for releasing and setting the latch.

4. A circuit-breaker, comprising movable main and shunt contacts pivoted together at a right angle, a fixed stud on which the shunt-contact is pivoted, a spring controlling the same, a magnetic blow-out and coöperating chute extending outwardly from the shunt-contact, and an operating-lever for opening and closing the circuit.

5. A circuit-breaker comprising movable main and shunt contacts pivoted together at right angles, a connecting-link 10 for effecting parallel motion, a spring giving the contacts a normal bias toward an open position, an operating-handle disconnected from the movable system but adapted to engage the same and close the contacts, a latch 13 to lock them set, and a detent controlled by the handle for locking or releasing the latch.

6. A circuit-breaker comprising fixed and movable contacts, a handle for closing the contacts, a latch engaging a sloping wall for holding the contacts set, a detent for locking the latch, and means for releasing the detent to permit the circuit to open.

7. A circuit-breaker comprising movable main and shunt contacts pivoted together at an angle, an operating-handle disconnected from the movable system but adapted to close the contacts, a spring giving a normal bias toward an opening movement, a latch engaging a beveled wall for holding them in closed position, and a detent pivoted on the same stud as the operating-handle and controlled thereby to lock or release the latch.

8. A circuit-breaker comprising movable main and shunt contacts, a handle disconnected therefrom but adapted to set them closed, a spring giving them a normal opening bias, a pivoted detent for locking them closed, means for releasing the detent, and a releasing-lug secured to the detent adapted to be tripped by the handle or the armature of an overload-magnet.

In witness whereof I have hereunto set my hand this 18th day of January, 1901.
